BRAKE BEAM SUPPORT

Edwin G. Busse, Chicago, Ill., assignor to Chicago
Railway Equipment Company, Chicago, Ill., a
corporation of Illinois

Application July 13, 1932, Serial No. 622,185

11 Claims. (Cl. 188—210)

This invention relates to railway brake beam guard, guide or support members and consists particularly in novel means of applying a fourth point support or safety guard to a railway truck.

5 One object of the present invention is to provide stable means for mounting the fourth point support or safety guard on a side frame.

Another object is to provide simplified means for mounting the support or guard on a frame 10 member, which means involves a minimum variation of the frame member.

Another object is to cheapen the frame member by eliminating the bracket or arm used in previous structures for facilitating mounting of 15 the fourth point support or safety guard.

These objects and others are attained by the structures illustrated in the accompanying drawings, in which

Figures 1 to 3, 5 to 8, 10, 11, 13, 14, and 16 are 20 vertical transverse sections through truck side frames illustrating various forms of the invention applied thereto.

Figure 4 is a view in perspective of a detail of the form in Figure 3.

25 Figure 9 is a side view of the structure shown in Figure 8.

Figure 12 is a detail section taken substantially on the line 12—12 of Figure 11.

Figure 15 is a horizontal section through a 30 truck side frame and illustrates another form of the invention.

In each of the figures, except Figure 16, the invention is illustrated as applied to the lower chord of a truck side frame casting of familiar construction, only the part of the frame to which the guard, guide or support bracket is attached being illustrated.

The frame includes a bolster spring seat 1 having a hollow box section portion beneath the same 40 including side walls 2 and 3 and a bottom wall 4, see Fig. 1. Side walls 2 and 3 are provided with aligned perforations which receive elongated bolt-like portion 5 at the outer end of a sidewardly extending arm 6 on the bracket 7 which mounts the 45 brake beam guard, guide or support member 8 by means of pin 9. The bolt-like portion 5 is threaded for nuts 10 and 11 which engage the outer surfaces of walls 2 and 3 and maintain the bracket 7 and the guard, guide or support device in the proper position on the side frame.

In Figure 2, the spaced side walls 12 and 13 beneath the bolster spring seat 14 are perforated at 15 and 16 for receiving the outer portion 17 of the sidewardly extending arm 19 on the guard, 55 guide or support bracket 19. Portion 17 at its

outer extremity includes depending legs 20, the outer extending along the outer surface of wall 12 and the inner extending through a perforation 21 in the bottom wall 23 of the side frame. Legs 20 receive pin 22, which abuts the bottom wall, 5 for maintaining the bracket in position. Perforations 15 and 16 are elongated transversely of arm 18 to permit the insertion or removal of legs 20 when the arm is turned ninety degrees from the position shown. An enlargement 24 is provided for abutting the inner surface of the wall 13.

In Figure 3, the sidewardly extending arm 25 on the guard, guide or support bracket extends through perforations 26 and 27 in the side walls 15 of the frame member and has a lug 28 and a hooked end 29 abutting the outer surfaces of the side walls. A U-shaped clip 30 rests upon a portion of arm 25 between the frame walls and the legs thereof depend through suitable perforations in the bottom wall 31 and receive a holding pin 32.

Perforations 26 and 27 and the hooked end 29 are shaped similarly to perforations 15 and 16 and legs 21, respectively, in Figure 2 to accommodate 25 insertion and removal of the bracket upon rotation of the bracket ninety degrees from the position shown.

In Figure 5, perforations 40 in the spaced side frame walls are provided with sidewardly extending perforated lugs 41 which receive pins 42 for securing the bracket arm 43 in position. A finger 44 depends from the portion of arm 43 inwardly of the side frame and curves beneath and abuts the bottom wall 45 of the frame. This 35 finger serves to relieve the arm 43 of bending forces caused by the weight of the guard, guide or support bracket.

In Figure 6, the bracket arm 33 extends through perforations 34 in the side walls of the frame 40 member and has a hook 35 at the outer end engaging the outer side wall and has a depression 36 between the walls which receives a pin 37 mounted in a bracket 38 projecting from the bottom wall 39 of the frame.

In Figure 7, the bracket arm 46 is held in position by means of an enlargement 47 abutting the inner side wall 48 and a pin or key 49 secured between bifurcations 50 at the outer end of the arm 50 by a cotter 51.

The bracket arm in Figure 8 is similar to that in Figure 7 except that an enlargement 52 is formed integral with the bracket arm 53 at the outer extremity and the perforations 54 in the spaced side walls of the frame member are made 55

large enough to receive the enlargement 52 when the bracket 55 is turned on its side, in the manner illustrated in Figure 9. Enlargements 52 and 56 abut the side walls of the frame, when in normal position, to hold the bracket in place.

5 In Figure 10, the bracket arm 57 is shown as extending through the inner wall 58 only of the side frame and enlargements 59 and 60 abut the surfaces of the wall for preventing tilting of the bracket. The bracket is turned 90 degrees, as in Figure 9, to permit insertion of the enlargement 60 through the perforation 61.

10 In Figures 11 and 12, the bracket arm 62 has enlargements 63 and 64 for holding the bracket 15 in position, and a bent flat spring 65 is applied to the arm inside the hollow side frame. Spring 65 engages the under surface of the bolster spring seat 66, and by forcing arm 62 against the lower edges of perforations in the spaced walls of the 20 side frame, prevents rattling of the bracket.

15 Enlargement 64 is elongated vertically and the openings in the side frame are elongated horizontally to permit passage therethrough of enlargement 64 when the bracket is rotated ninety 25 degrees from the position shown, corresponding to the showing in Figures 8 and 9.

20 In Figures 13 and 14, other means of preventing rattling are illustrated. Figure 13 shows a spring 67 applied to the outer end of the arm 68 and compressed between the outer frame wall 69 and a washer 67a forming an abutment for the outer end of the spring and held in place by a key 67b. Enlargements 70 abutting the inner frame wall 71 limit the movement of the bracket arm. 30 The inner enlargement corresponds in shape to the similar element 52 in Figure 8, and the opening in the left hand portion of the side frame is elongated, as opening 54 in Figure 9, to permit insertion and removal of the bracket arm. In 35 Figure 14 the inner enlargement 72 is spaced from the inner wall 73 of the side frame and a coiled spring 74 is compressed between enlargement 72 and the inner wall. The outer enlargement is passed through the openings in the side frame in 40 the manner previously described for similar elements in Figures 8, 11, and 13.

45 Figure 15 shows a one-piece strap-like member including inner portions 75 for association with the brake beams and an outwardly offset intermediate portion 76 which abuts the wall 77 of the side frame. The strap is secured to the frame by means of a bracket device including bolts 78 extending through spaced walls 77 and 79, plates 80 being provided to strengthen the connection.

50 In Figure 16, the guard, guide or support member 81 is shown carried from above by means of a bar 82 which extends through the portion 83 of the side frame above the bolster opening 84 and is secured in place by a pin or key 85. The bar 55 82 may abut the hanger bracket 86, and a lug 87, shown dotted, provided to stabilize the guard or support. In this case, a wall of member 83 and the inner surface of bracket 86 constitute spaced parts of the truck side frame balancing the guard, 60 guide or support bar 82.

65 In each of the forms, the guard, guide or support bracket is attached to a frame part without the provision of any rigid inwardly extending bracket or arm which would increase the cost of the truck frame and be liable to breakage. Moreover, in each of the forms, except that in Figure 70 10, the weight of the bracket is distributed between substantially spaced walls, the inner wall receiving downward pressure and the outer wall upward pressure due to the tendency of the bracket to tilt 75

about the inner wall as a pivot. In the form shown in Figure 10, the weight of the bracket is distributed over a substantial portion of the single supporting wall.

The use of the novel support bracket is not 5 limited to the type of side frame illustrated, and in fact the attachment of a guard, guide or support device to another truck structural part, such as a transom or spring plank, would be facilitated by utilization of the novel features of the invention. 10 The particular point of attachment of the bracket to its supporting member is not essential.

15 Any form of guard, guide or support member may be used and a resilient strap member may be provided for engaging a chair depending from the beam, or the device may be spaced beneath the beam serving only as a safety guard, or the beam may be suspended from above in the manner illustrated in my co-pending application Serial No. 550,238, filed July 11, 1931. The invention covers 20 broadly the means illustrated for attaching a brake beam guard, guide or support member to a truck part, and exclusive use of all such devices as come within the scope of the appended claims is contemplated.

25 What is claimed is:

1. In a railway truck, a side frame member having a hollow interior, a brake beam guard, guide or support device having a part projecting sidewardly of said member and a portion within 30 the hollow interior thereof, and means cooperating with said portion and engaging an inner wall of said hollow member for maintaining said device in position.

2. In combination, a railway truck part having 35 a wall, a brake beam guard, guide or support device having a part extending away from said part and a portion associated with and extending through said wall, and a yielding element cooperating with said truck part and said portion to 40 prevent rattling of said frame part and said device.

3. In combination, a railway truck part including a wall having an aperture therein, and a brake beam guard, guide or support member 45 having a projection shaped to pass through said aperture when said member is rotated from its operative position and to engage said wall when said member is rotated to said operative position to assist in securing said member to said wall.

4. In a railway truck, a side frame member including side and bottom walls, a brake beam guard, guide or support device including a part projecting sidewardly from said member and a portion extending between said side walls, and means cooperating with said portion and said bottom wall to maintain said device in position.

5. In a railway truck, a side frame including a hollow lower member with a pair of walls having spaced apertures, and a brake beam guard, guide or support device projecting sidewardly from said lower member and through said apertures and having a portion extending into the interior of said member and secured thereto.

6. In combination, a truck structural member including angularly disposed walls each with a perforation, and a brake beam guard, guide or support device including a part insertable in one position through the perforation in one of said walls, said device being rotatable to cause said part to extend through the perforation in the other wall to prevent withdrawal of said part through said first-mentioned perforation, and means for maintaining said part in the last defined position.

7. In combination, a railway truck structural member including angularly disposed walls each with a perforation, and a brake beam guard, guide or support device including an angular part insertable in one position through the perforation in one of said walls and an enlargement on one leg of said part limiting the passage of said part through said perforation, said device being rotatable to cause the other leg of said part to extend through the perforation in the other of said walls preventing withdrawal of said part through said first-mentioned perforation, and means for maintaining said part in the last defined position.

15 8. In combination, a railway truck structural member having spaced elements, and a brake beam guard, guide or support device including a part extending through at least one of said elements, means securing said part to said member, and a spring element engaging said part and said member for preventing rattling.

9. In combination, a railway truck structural member having a plurality of walls, a brake

beam guard, guide or support device including a part extending through at least two of said walls and having an abutment adjacent one of said walls, and spring means between said abutment and said one of said walls for preventing rattling.

5

10 10. In combination, a railway truck structural member having spaced walls each with a perforation, and a brake beam guard, guide or support device including a part for association with said member, said part having means insertable in one position through said perforations and rotatable to a position to prevent withdrawal of said part through said perforations, and a spring cooperating with said means and said member to prevent rattling of said device.

10

15 11. In combination, a railway truck side frame having spaced side walls and a separately formed brake beam guard, guide, or support device including a portion extending through both of said walls, and yielding elements cooperating with said portion and at least one of said walls to maintain said device in position.
